UNITED STATES PATENT OFFICE

CHARLES A. MOORE, OF EDINA, MINNESOTA

AIR CONDITIONING APPARATUS FOR STORAGE ROOMS

Application filed March 18, 1924, Serial No. 700,060. Renewed December 2, 1929.

My invention relates to improvements in air conditioning apparatus for storage rooms.

An object of the invention is to supply improved and efficient apparatus for conditioning the atmosphere in storage rooms, the same being adapted to provide for effective ventilation, without or in combination with heating or with refrigeration.

A further object is to supply in an apparatus of the instant nature, an improved temperature affecting appliance operating in accordance with the natural laws to provide ventilation, the same being convertible for primary heating or refrigerating purposes and serving naturally under its converted uses to augment convective and diffused circulation of air in the system normally effected thereby.

Another object is to provide for forcing ventilation, augmented or not by the heating or cooling medium in the temperature affecting appliance, whereby convective and diffused movement of air is stimulated and further heated or refrigerated to compensate for the relatively larger volume of air employed in the conditioning process operating at its maximum capacity.

With the foregoing and other objects in view, which will appear in the following description, the invention resides in the novel combination and arrangement of parts and in the details of construction hereinafter described and claimed.

In the drawings, Fig. 1 is a view partly in elevation and partly in section, the same illustrating a housing and a storage room structure associated therewith, also the temperature affecting appliance and companion devices in said housing, certain of the baffles in the housing being omitted and broken away for the sake of clearness; Fig. 2 is a horizontal sectional view taken on the line 2—2 of Fig. 1; Fig. 3 is a vertical sectional view taken on the line 3—3 of Fig. 2; Fig. 4 is a similar view in detail taken on the line 4—4 of Fig. 1; Fig. 5 is a vertical sectional view in detail taken on the line 5—5 of Fig. 1, the upper portions of the tiers of coils being broken away at the upper portion of the housing for the sake of clearness; Fig. 6 is a

perspective view in detail of a pair of conduits for a storage room; Fig. 7 is a vertical, central, sectional view of the temperature affecting appliance, said view being taken as on the line 7—7 of Fig. 1; Fig. 8 is a horizontal sectional view in detail taken on the line 8—8 of Fig. 7; Fig. 9 is a plan view, in detail, of the temperature affecting appliance and Fig. 10 is a view largely illustrating the principal features of the apparatus in simple, but purely diagrammatic form.

In the illustrated embodiment of my invention, a housing A surmounts a plurality of superimposed storage rooms B. A partition 10 in the housing A divides the space therein into an appliance chamber *a*, and a coil chamber *b*, which, at times, are herein-after referred to as primary and secondary chambers, respectively. Each storage room B has two conduits 11 and 12 therefor, the former leading downward from a point in the floor of the coil chamber to the ceiling of the room, thence along the ceiling medially longitudinally thereof in the form of a branch 11^a. The companion conduit 12 for each conduit 11 leads downward from a point near the ceiling of the appliance chamber *a* to the ceiling of its respective storage room B, thence along said ceiling, closely paralleling branch 11^a, in the form of a branch 12^a. Said conduit branches 11^a and 12^a are spaced slightly from their respective ceilings, each of the former having a longitudinal slot 11^b in its lower side and each of the latter having a similar slot 12^b in the upper side thereof.

The primary chamber *a* contains a temperature affecting appliance C and two conventional blowers D and E, preferably of the centrifugal type. The inlet 13 of the blower D opens into the primary chamber *a* and the outlet 14 thereof into the secondary chamber *b*, while the inlet 15 of the blower E opens into the secondary chamber *b* and the outlet 16 thereof into the primary chamber *a*. These blowers are independently operable and like the temperature affecting appliance C will be more fully hereinafter described.

Tiers of connected pipes or coils 17 are arranged in groups in the secondary chamber *b*

and in connection with baffles 18, 19 and 20, form a winding path (Fig. 2) for air from the outlet 14 of the blower D and from a port 21 in the partition 10 to the conduits 11, which, 5 as above explained communicate with said chamber b. The port 21 just mentioned is located at the bottom of the partition 10 and is provided with an adjustable closure 22, a similar adjustable closure 23 being provided 10 for an elevated port 24 in said partition 10. In one tier of pipes 17 in each of the central groups, the pipes are arranged closely together and in such relation constitute baffle walls with which the baffles 18, 19, 20 are associated.

The temperature affecting appliance C includes two upright ducts c' and c². The outer duct c' consists of a cylindrical base 25, coiled pipe 26^a carried by the base 25 and constituting a cylindrical container body 26, a cap 28 on said body and a tubular terminal 29 rising from said cap 28. The inner duct c², includes a tubular body 30 spaced axially within the container body 26, said body 30 having a tubular terminal 31 rising therefrom through the cap 28 of the outer duct c'. The terminal 29 is fitted near its upper end with a valve or damper 32, a similar valve 33 being similarly applied to the terminal 31. The base 25 of the outer duct c' is formed with a port 34 fitted with a damper 35. The lower end of the inner duct c² has a branch 36 leading outward through the base 25 and the wall of the housing A to the outer air. Said lower end of said duct c² also has a branch 37 leading outward through said base 25 into the primary chamber a and is further supplied with a port 38 opening into the outer duct c' at the base thereof. The branches 36, 37 and port 40 are respectively fitted with dampers 39, 40 and 41 and a fourth damper 42 is arranged in the duct c² just beneath the junction of said duct with the branch 37. A flue 43 rising from the housing A joins the two terminals 29, 31 of the ducts c', c² through two branches 44, 45, said branches being respectively fitted with dampers 46, 47.

Associated with the temperature affecting appliance C are two upright pipes 48, 49, the same being located in the secondary chamber b and ending short of the ceiling thereof at their upper ends and short of the floor of said chamber at their lower ends. An inter-chamber duct 50 reaching horizontally through the partition 10 connects with the pipe 48 in the secondary chamber b near the upper end of said pipe. The end of said inter-chamber duct within the primary chamber a is supplied with branches 51, 52, the former having a damper 53 therein and connecting with the terminal 29 of the apparatus duct c', while the latter has a damper 54 therein and is connected with the terminal 31 of the apparatus duct c². A second inter-chamber duct 55 reaches horizontally through the partition 10

and connects, within the secondary chamber b, with the pipe 49 near its upper end. The end of said second inter-chamber duct 55 within the primary chamber a is supplied with branches 56, 57, the former having a damper 58 therein and connecting with the terminal 29 of the apparatus duct c', while the latter branch has a damper 59 therein and is connected with the terminal 31 of the apparatus duct c². The upper ends of the pipes 48, 49 are respectively fitted with dampers 60, 61, while the lower ends of said pipes are respectively fitted with dampers 62, 63.

In use, the apparatus is operated to meet practically every need in properly conditioning the air in the storage rooms for the preservation of perishable lading therein. The apparatus alone and without the use of the blowers D, E and coils 17 suffices under many conditions, but when inadequate is augmented by the use of said blowers and coils.

Under primary refrigeration, a cooling medium is introduced to the coiled pipe forming the body 26 of the duct c', the effect of which is to produce a downward movement of air in both of the ducts c' and c². With dampers 32, 35 and closure 22 open, air descends from the upper portion of chamber a, through terminal 29 and duct c' into the lower portion of said chamber, thence passes said open closure 22 and descends through conduits 11 and branches 11^a into the rooms B. Rising along the relatively warm walls of said rooms, air ascends to branch conduits 12^a, thence passes through conduits 12 back to the ceiling of chamber a. With dampers 33, 42 and 41 open, air also may descend from the upper portion of chamber a to the lower portion thereof through terminal 31, duct c² and the lower portion of duct c'. In addition to this simple circulation of refrigerated air in the rooms B, the user may introduce fresh air from the outside and expel used air from the system. This is accomplished by opening damper 46 to admit air from the flue 43 to the terminal 29 and by opening damper 39 with dampers 40 and 41 closed to direct the descending air in duct c² to the outside through branch 36. And any recirculation of air in the rooms B may be avoided by closing damper 32 in terminal 29, whereby none of the previously used air is permitted to enter the appliance C through an avenue opening back into chamber a.

To increase the refrigerating effect produced in introducing a cooling medium to the coiled pipe forming the body 26 of duct c', a similar medium is introduced to the coiled pipes 17 in chamber b. Under this condition and with closure 23 open, air coming into chamber a from conduit 12 may pass into chamber b. Such air, cooled by the coils 17, will descend in chamber b and enter conduits 11 through which refrigerated air from the appliance C passes to

the rooms B. Air may be skimmed off from the ceiling of chamber b and put through duct c' to be dehumidified in its transit to conduits 11, by opening either or both of dampers 60 and 53 or dampers 61 and 58 or all of them. And such air may be put through duct c' to the outside by opening damper 54 or damper 59, dampers 53 and 58 being closed. To stimulate the movement of air in the system under refrigeration and to increase the supply of fresh air, when ventilating alone or under combined ventilation and recirculation, blower D is set in operation, with closures 22 and 23 shut. Air from chamber a then enters chamber b under pressure, which is exerted to impel the refrigerated air into conduits 11 and back through conduits 12, all in the direction of movement under gravitation. If it should be desired to set up a local recirculation of some of the air in the chambers a and b, the same may be accomplished by opening dampers 62 and 53 or 63 and 58 or all of them, whereupon air will be forced up in pipe 48 or pipe 49 or both to terminal 29 where it joins the air flowing downwardly therethrough into duct c'. Instead of setting up said local recirculation, dampers 53 and 58 may be closed and damper 54 or 59, or both, opened to permit of the expulsion of air to the outside from the floor of chamber b, through terminal 31, duct c' and branch 36.

A heating medium may be introduced to the coiled pipe forming the body 26 of duct c' and lower E started with closures 22 and 23 shut. Air is then drawn into chamber b from the rooms B through conduits 11, thence blown into chamber a, whence air is impelled past open damper 35, thence blown into chamber a, whence air is impelled past open damper 35, thence upward in duct c' and terminal 29 past open damper 32 into the upper portion of the chamber a, thence is impelled down conduits 12 to the rooms, thus completing a heating cycle. Fresh air may be taken into the circulation by opening dampers 60, 54, 42 and 39 and closing dampers 41 and 40, the fresh air from without finding ingress to chamber b on the suction side of blower E through branch 36, duct c', terminal 31, branch 52, duct 50 and pipe 48. Air is exhausted from the system by opening damper 46, thus furnishing a way for the egress of air from terminal 29 through flue 43. A heating medium introduced to the coils 17 augments the heating capacity of the system as will be readily comprehended.

Without the use of a heating or cooling medium, a combined forced ventilation and recirculation may be had by putting the blower E into operation and shutting closures 22, 23. With dampers 47, 54 and 62 open and dampers 40 and 42 closed, fresh air will be drawn from the outside through flue 43, ter-

70 minal 31, duct 50, pipe 48 and chamber b to blower E. Air will also be drawn from the rooms B through conduits 11. Issuing from said blower E air is forced into chamber a, a part of it being impelled back to rooms B through pipe 12 and a part thereof forced to the outside past open dampers 35, 41 and 39 through the lower portion of duct c' and through branch 36.

A natural internal circulation of air in the system, without the use of a heating or cooling medium, may be had with or without admitting and exhausting air. For example, if it is colder outside than inside, air settling along the walls of chambers a and b 75 flows from the floors of said chambers down through conduits 11 to rooms B. Rising centrally of said rooms B, air returns to chambers a and b through conduits 12. If it is desired to freshen the air in chamber a, 80 air from without will ascend to the ceiling of said chamber through branch 36, past open dampers 39, 41, thence upward through duct c' and thence through terminal 29 past open damper 32. Compensating for the air finding ingress to chamber a, air is exhausted 85 from the floor of said chamber, the same ascending through branch 37, past open damper 40, thence upward through duct c', thence through terminal 31, thence past open damper 47 and thence out through flue 43.

Thus, in the different movements of air arranged to provide the desired atmospheric conditions in the rooms B, it will be understood that the natural tendency of the air 100 to rise or fall according to the relative temperatures is employed to advantage.

Changes in the specific form of my invention, as herein disclosed, may be made within the scope of what is claimed without departing from the spirit of my invention.

Having described my invention, what I claim as new and desire to protect by Letters Patent is:

1. In an apparatus of the class described, 110 the combination with a structure constituting a plurality of superimposed storage rooms, a housing superimposing said structure, a partition in said housing forming a first chamber and a second chamber, said partition having an upper and a lower port therethrough, an adjustable closure for each port, a pair of conduits for each room, each conduit having a horizontal branch reaching through the upper portion of its respective room, one conduit communicating with the second chamber at the bottom thereof and having a longitudinal opening in the lower side of its horizontal branch, the other conduit 115 communicating with the first chamber at the top thereof and having a longitudinal opening in the upper side of its horizontal branch, an appliance in the first chamber including two upright ducts, means for affecting the 120 temperature thereof, one duct having a 125

valved opening at the lower portion thereof in communication with the first chamber, valved means associated with said ducts and selectively adapted to bring the upper ends thereof into communication with the outer air and with the first chamber, valved means associated with the lower end of the second duct and adapted selectively to bring the same into communication with the outer air, the first chamber and the first duct, a pair of upright pipes in the second chamber, valves at the ends of said pipes, inter-chamber ducts for said pipes, each inter-chamber duct being joined at one extremity with its respective pipe near the upper end thereof and having branches at its other end connected with the appliance ducts near their upper ends, valves in said duct branches, temperature affecting means in the second chamber and blower mechanisms selectively operable for blowing air into the second chamber from the first chamber and vice versa.

2. In an apparatus of the class described, the combination with a structure including a storage room, and a chamber superimposing said room, a pair of conduits for said storage room, one leading from the upper portion of the room to the upper portion of said chamber and the other from the lower portion of said chamber to the upper portion of said room, and an appliance in said chamber comprising two upright ducts and means for affecting the temperature thereof, one duct opening at its upper end near the ceiling of the chamber and at its lower end into the outer air, the other duct opening at its upper end into the outer air and at its lower end into the chamber.

3. In an apparatus of the class described, the combination with a structure including a plurality of storage rooms and a chamber associated therewith, a pair of conduits for each storage room, each of said pairs of conduits bringing its respective storage room into communication with said chamber, one conduit of each pair leading from the upper portion of a room to the upper portion of said chamber and the other from the lower portion of said chamber to said room, and two ducts in said chamber, one duct opening at its upper end near the ceiling of the chamber and at its lower end into the outer air, the other duct opening at its upper end into the outer air and at its lower end into the chamber.

4. In an apparatus of the class described, the combination with a structure including a storage room and a chamber, a pair of conduits bringing the storage room into communication with said chamber, one conduit leading from the upper portion of the room to the upper portion of said chamber and the other from the lower portion of said chamber to said room at an elevation beneath the opening of the other duct into said room,

and an appliance in said chamber comprising two upright ducts and means for affecting the temperature thereof, the upper end of one duct opening near the ceiling of the chamber, the lower end of said duct having communication severally or simultaneously with the outer air and with the chamber, the lower end of the other duct having communication with said chamber and the upper end thereof having communication severally or simultaneously with said chamber and the outer air.

5. In an apparatus of the class described, the combination with a structure including a storage room and a first chamber and a second chamber superimposing said room, said chambers being in valved communication, one with the other, at the upper and lower portions thereof, a pair of conduits, both opening at their lower ends into the storage room, one opening at its upper end in the upper portion of the first chamber, the other opening at its upper end at the lower portion of the second chamber, an appliance in the first chamber comprising two upright ducts and means for affecting the temperature thereof, one duct opening at its lower end into the outer air, the other duct communicating at its upper end with the outer air and opening at its lower end into the first chamber and temperature affecting means within said second chamber.

6. In an apparatus of the class described, the combination with a structure including a storage room and a first chamber and a second chamber superimposing said room, said chambers being in valved communication one with the other at the upper and lower portions thereof, a pair of conduits, both opening at their lower ends into said storage room, one opening at its upper end in the upper portion of the first chamber, the other opening at its upper end at the lower portion of the second chamber, an appliance in the first chamber comprising two upright ducts, means for affecting the temperature thereof, one duct opening at its upper end near the ceiling of the first chamber and at its lower end into the outer air, the other duct communicating at its upper end with the outer air and opening at its lower end into the first chamber, a passageway leading from the upper portion of the second chamber to said first duct of the appliance at its upper end and temperature affecting means within said second chamber.

7. In an apparatus of the class described, the combination with a structure including a storage room and a first chamber and a second chamber superimposing said room, said chambers being in valved communication, one with the other at the upper and lower portions thereof, a pair of conduits, both opening at their lower ends into said storage room, one opening at its upper end in the

upper portion of the first chamber, the other opening at its upper end at the lower portion of the second chamber, an appliance in the first chamber comprising two upright ducts and means for affecting the temperature thereof, one duct opening at its upper end near the ceiling of the first chamber and at its lower end into the outer air, the other duct communicating at its upper end with the outer air and opening at its lower end into the first chamber, a passageway leading from the upper portion of the second chamber to said second duct of the appliance at its upper end and temperature affecting means within the second chamber.

8. In an apparatus of the class described, the combination with a structure including a storage room and a first chamber and a second chamber superimposing said room, said chambers being in valved communication, one with the other, at the upper and lower portions thereof, a pair of conduits, both opening at their lower ends into said storage room, one opening at its upper end in the upper portion of the first chamber, the other opening at its upper end at the lower portion of the second chamber, an appliance in the first chamber comprising two upright ducts and means for affecting the temperature thereof, one duct opening at its upper end near the ceiling of the first chamber and at its lower end into the outer air, the other duct communicating at its upper end with the outer air and opening at its lower end into said first chamber, an inter-chamber duct leading from the upper portion of the second chamber to the first chamber, branches leading from said inter-chamber duct, one joining said first duct near the upper end thereof and the other joining the said second duct near its upper end, valves in said branches and temperature affecting means within said second chamber.

9. In an apparatus of the class described, the combination with a structure including a storage room and a first chamber and a second chamber superimposing said room, said chambers being in valved communication, one with the other, at the upper and lower portions thereof, a pair of conduits, both opening at their lower ends into said storage room, one opening at its upper end in the upper portion of the first chamber, the other opening at its upper end at the lower portion of the second chamber, an appliance in the first chamber comprising two upright ducts and means for affecting the temperature thereof, one duct opening at its upper end near the ceiling of the first chamber and at its lower end into the outer air, the other duct communicating at its upper end with the outer air and opening at its lower end into the first chamber, a passageway leading from the lower portion of the second chamber to said first duct of the appliance at its upper

end and temperature affecting means within said second chamber.

10. In an apparatus of the class described, the combination with a structure including a storage room and a first chamber and a second chamber superimposing said room, said chambers being in valved communication, one with the other, at the upper and lower portions thereof, a pair of conduits, both opening at their lower ends into said storage room, one opening at its upper end in the upper portion of the first chamber, the other opening at its upper end at the lower portion of the second chamber, an appliance in the first chamber comprising two upright ducts and means for affecting the temperature thereof, one duct opening at its upper end near the ceiling of the first chamber and at its lower end into the outer air, the other duct communicating at its upper end with the outer air and opening at its lower end into said first chamber, a passage way leading from the lower portion of the second chamber to said second duct of the appliance at its upper end and temperature affecting means within the second chamber.

11. In an apparatus of the class described, the combination with a structure including a storage room and a first and a second chamber superimposing said room, said chambers being in valved communication, one with the other, at the upper and lower portions thereof, a pair of conduits, both opening at their lower ends into said storage room, one opening at its upper end in the upper portion of the first chamber, the other opening at its upper end at the lower portion of the second chamber, an appliance in the first chamber comprising two upright ducts and means for affecting the temperature thereof, one duct opening at its upper end near the ceiling of the first chamber and at its lower end into the outer air, the other duct communicating at its upper end with the outer air and opening at its lower end into said first chamber, an inter-chamber duct leading from the lower portion of the second chamber to the first chamber, branches leading from said inter-chamber duct, one joining said first appliance duct near the upper end thereof and the other joining said second appliance duct near its upper end, valves in said branches and temperature affecting means within said second chamber.

12. In an apparatus of the class described, the combination with a structure including a storage room and a first and a second chamber superimposing said room, a pair of conduits for said storage room, one opening at its upper end in the upper portion of the first chamber and at its lower end near the ceiling of the storage room, the other opening at its upper end at the lower portion of the second chamber and at its lower end at a point beneath the opening of said first con-

duit in said storage room, an appliance in the first chamber comprising two upright ducts, and means for refrigerating the same, one duct opening at its upper end near the ceiling of the first chamber and at its lower end into the outer air, the other duct opening at its upper end into the outer air and at its lower end into the first chamber, temperature affecting means within the second chamber, and blower mechanism for blowing air from the first chamber into the second chamber.

13. In an apparatus of the class described, the combination with a structure including a storage room and a primary chamber and a secondary chamber, a pair of conduits for said storage room, one opening at one end in the upper portion of the primary chamber and at its other end near the ceiling of the storage room, the other conduit opening at one end at the lower portion of the secondary chamber and at its other end at a point beneath the opening of said first conduit in said storage room, an appliance in the primary chamber comprising two upright ducts and refrigerating means affecting said ducts, one duct opening at its upper end near the ceiling of the primary chamber and at its lower end into the outer air, the other duct opening at its upper end into the outer air and at its lower end into the primary chamber, refrigerating means in the secondary chamber, and blower mechanism for blowing air from the primary chamber into the secondary chamber.

14. In an apparatus of the class described, the combination with a structure including a storage room and a primary chamber and a secondary chamber, a pair of conduits for said storage room, one opening at one end in the upper portion of the primary chamber and at its other end near the ceiling of the storage room, the other conduit opening at one end at the lower portion of the secondary chamber and at its other end at a point beneath the opening of said first conduit in said storage room, an appliance in the primary chamber comprising two upright ducts and refrigerating means arranged to affect said ducts, one duct opening at its upper end near the ceiling of the primary chamber and at its lower end into the outer air, the other duct opening at its upper end into the outer air and at its lower end into the primary chamber, a passageway leading from the upper portion of the secondary chamber to the upper end of one of said appliance ducts, refrigerating means in the secondary chamber and blower mechanism for blowing air from the primary chamber into the secondary chamber.

15. In an apparatus of the class described, the combination with a structure including a storage room and a primary chamber and a secondary chamber, a pair of conduits for

said storage room, each opening at one end thereof in the storage room, one opening at the other end in the upper portion of the primary chamber, the other conduit opening at its other end at the lower portion of the secondary chamber, an appliance in the primary chamber comprising two upright ducts and refrigerating means therefor, one duct opening at its upper end near the ceiling of the primary chamber and at its lower end into the outer air, the other duct opening at its upper end into the outer air and at its lower end into the primary chamber, a passageway leading from the upper portion of the secondary chamber to the upper end of said second duct of the appliance, refrigerating means in the secondary chamber, and blower mechanism for blowing air from the primary chamber into the secondary chamber.

16. In an apparatus of the class described, the combination with a structure including a storage room and a primary chamber and a secondary chamber, a pair of conduits for said storage room, one opening at one end in the upper portion of the primary chamber and at its other end near the ceiling of the storage room, the other conduit opening at one end at the lower portion of the secondary chamber and at its other end at a point beneath the opening of said first conduit in said storage room, an appliance in the primary chamber comprising two upright ducts and means for refrigerating the same, one duct opening at its upper end near the ceiling of the primary chamber and at its lower end into the outer air, the other duct opening at its upper end into the outer air and at its lower end into the primary chamber, a passageway leading from the upper portion of the secondary chamber to the upper end of said first duct of the appliance, refrigerating means within the secondary chamber and blower mechanism for blowing air from the primary chamber into the secondary chamber.

17. In an apparatus of the class described, the combination with a structure including a storage room and a primary chamber and a secondary chamber, a pair of conduits for said storage room, one opening at one end in the upper portion of the primary chamber and at its other end near the ceiling of the storage room, the other conduit opening at one end at the lower portion of the secondary chamber and at its other end at a point beneath the opening of said first conduit in said storage room, an appliance in the primary chamber comprising two upright ducts, refrigerating means arranged to affect said ducts, one duct opening at its upper end near the ceiling of the primary chamber and at its lower end into the outer air, the other duct opening at its upper end into the outer air and at its lower end into the primary chamber.

chamber, a passageway leading from the lower portion of the secondary chamber to the upper end of one of said appliance ducts, refrigerating means in the secondary chamber and blower mechanism for blowing air from the primary chamber into the secondary chamber.

18. In an apparatus of the class described, the combination with a structure including a storage room and a first chamber and a second chamber, a pair of conduits for the storage room, each opening at one end thereof in said room, one opening at the other end in the upper portion of the first chamber, the other conduit opening at its other end at the lower portion of the second chamber, an appliance in the first chamber comprising two upright ducts and means for refrigerating the same, one duct opening at its upper end near the ceiling of the first chamber and at its lower end into the outer air, the other duct communicating at its upper end with the outer air and opening at its lower end into the first chamber, refrigerating means in the second chamber and blower mechanism for blowing air from the first chamber into the second chamber.

19. In an apparatus of the class described, the combination with a structure including a storage room and a primary chamber and a secondary chamber, the storage room being in communication with the primary chamber and with the secondary chamber, an appliance in the primary chamber comprising two upright ducts and means for affecting the temperature thereof, one duct opening at its upper end near the ceiling of the primary chamber and at its lower end into the outer air, the other duct communicating at its upper end with the outer air and opening at its lower end into the primary chamber, temperature affecting means in the secondary chamber and blower mechanism for blowing from the primary chamber into the secondary chamber.

20. In an apparatus of the class described, the combination with a structure including a storage room and a primary chamber and a secondary chamber, a pair of conduits for the storage room, each opening at one end thereof into said room, one opening at the other end in the upper portion of the primary chamber, the other conduit opening at the other end at the lower portion of the secondary chamber, an appliance in the primary chamber comprising two upright ducts and temperature affecting means therefor, one duct opening at its upper end near the ceiling of the primary chamber and at its lower end into the outer air, the other duct communicating at its upper end with the outer air and opening at its lower end into the primary chamber, temperature affecting means in the secondary chamber and blower mechanism for bringing the lower end of said second duct into communication with each other, and valved means bringing the lower end of said second duct

mechanism for blowing air from the primary chamber into the secondary chamber.

21. In an apparatus of the class described, the combination with a structure including a storage room and a primary chamber and a secondary chamber, said chambers having valved communication, one with the other, at the upper portions thereof, a pair of conduits for the storage room, each opening at one end thereof in said room, one opening at the other end in the upper portion of the primary chamber, the other conduit opening at its other end at the lower portion of the secondary chamber, an appliance in the primary chamber comprising two upright ducts and temperature affecting means therefor, one duct opening at its upper end near the ceiling of the primary chamber and at its lower end into the outer air, the other duct communicating at its upper end with the outer air and opening at its lower end into the primary chamber, temperature affecting means in the secondary chamber, and blower mechanism for blowing air from the primary chamber into the secondary chamber.

22. In an apparatus of the class described, the combination with a structure including a storage room and a primary chamber and a secondary chamber, a pair of conduits for said room, one leading from the upper portion of the primary chamber to said room and the other leading from the lower portion of the secondary chamber to said room, an appliance in the primary chamber comprising two upright ducts and temperature affecting means associated with said ducts, a passageway leading from the upper end of one duct into the secondary chamber at the upper portion thereof, the lower end of said duct communicating with the outer air, the lower end of the other duct communicating with the primary chamber at its lower portion and the upper end of said second duct communicating with the outer air, temperature affecting means associated with the secondary chamber, and blower mechanism for blowing air from the secondary chamber into the primary chamber.

23. In an apparatus of the class described, a chamber, an appliance therein including two upright ducts, the upper ends of said ducts opening near the ceiling of the chamber, temperature affecting means associated with said ducts, branches, one for each duct, leading from points near the upper ends of said ducts to the outer air, valves for severally closing or opening said ducts to the outer air through said branches, the lower end of one duct having a valved port at the bottom thereof, valved means bringing the lower end of the other duct into communication with the outer air, valved means bringing the lower portions of said ducts into communication with each other, and valved means bringing the lower end of said second duct

into communication with the lower portion of the chamber.

24. In an apparatus of the class described, a chamber, an appliance therein including two upright ducts valved at their upper ends and piped from points near said ends to the outer air, temperature affecting means associated with said ducts, the lower end of one duct having a valved port at the bottom thereof, valved means bringing the lower end of the other duct into communication with the outer air, valved means bringing the lower portions of said ducts into communication with each other, and valved means bringing the lower end of said second duct into communication with the lower portion of the chamber.

25. In an apparatus of the class described, a chamber, an appliance therein including two upright ducts valved at their upper ends and piped from points near said ends to the outer air, the lower end of one duct having a valved port at the bottom thereof, valved means bringing the lower end of the other duct into communication with the outer air, valved means bringing the lower portions of said ducts into communication with each other, and valved means bringing the lower end of said second duct into communication with the lower portion of the chamber.

26. In combination, a storage room and an appliance chamber, a pair of conduits establishing communication between the storage room and the appliance chamber, one conduit leading to the upper portion of said chamber from the upper portion of the room and including a branch disposed longitudinally medially of the room in elevated position adjacent the ceiling thereof, said branch being open along the top thereof to receive air at the ceiling, the second conduit leading from the lower portion of said chamber and including a branch disposed alongside said first branch, said second branch being open along the lower side thereof, and an appliance in said chamber comprising two upright ducts and refrigerating means for affecting the temperature thereof, one duct opening at its upper end near the ceiling of the chamber and at its lower end to the outer air, the other duct opening at its upper end into the outer air and at its lower end into the chamber.

27. In combination, a storage room and an appliance chamber, a pair of conduits establishing communication between the storage room and the appliance chamber, one conduit leading to the upper portion of said chamber from the upper portion of the room and including a branch disposed longitudinally medially of the room in elevated position adjacent the ceiling thereof, said branch being open along the top thereof to receive air at the ceiling, the second conduit leading from the lower portion of said chamber and

including a branch disposed alongside said first branch, said second branch being open along the lower side thereof for the egress of air therefrom, means for impelling air along said second conduit, and an appliance in said chamber comprising two upright ducts and refrigerating means for affecting the temperature thereof, one duct opening at its upper end near the ceiling of the chamber and at its lower end to the outer air, the other duct opening at its upper end into the outer air and at its lower end into the chamber.

28. In combination, a storage room and an appliance chamber, a pair of conduits establishing communication between the storage room and the appliance chamber, one conduit leading to the upper portion of said chamber from the upper portion of the room and including a branch disposed longitudinally medially of the room in elevated position adjacent the ceiling thereof, said branch being open along the top thereof to receive air at the ceiling, the second conduit leading from the lower portion of said chamber into the upper portion of said room and arranged to discharge air into the room alongside but beneath said branch of said first conduit, means for impelling air through said second conduit from said chamber, and an appliance in the chamber comprising two upright ducts and refrigerating means for affecting the temperature thereof, one duct opening at its upper end near the ceiling of the chamber and at its lower end to the outer air, the other duct opening at its upper end into the outer air and at its lower end into the chamber.

29. In combination, a storage room and a source of refrigerated air supply exteriorly of the room, a conduit for conducting gravitating air from said source into the room, said conduit including a branch extending medially along the length of the ceiling of the room and open at its lower portion for the egress of air therefrom along its length, and a conduit for the escape of air from the upper stratum in the room medially thereof.

30. In combination, a storage room and a source of refrigerated air supply exteriorly of the room, a conduit for conducting gravitating air from said source into the room, said conduit including a branch extending medially along the length of the ceiling of the room and open at its lower portion for the egress of air therefrom along its length, and a second conduit leading from the room and including a branch disposed alongside said first branch, said second branch being open at its upper portion for the ingress thereof along its length in a stratum superimposing the level of egress from said first branch.

31. In combination, a storage room and a source of temperature affected air supply, a conduit for conducting air from said source

into the room, said conduit including a branch extending medially along the ceiling of the room and open at its upper portion for the egress of air therefrom along its length, and a conduit for the escape of air from the room, said second conduit opening into the upper portion of the room medially thereof at a level lower than the egress level of said first conduit.

32. In combination, a storage room and a source of temperature affected air supply, a conduit for conducting air from said source into the room, said conduit including a branch extending medially along the ceiling of the room and open at its upper portion for the egress of air therefrom along its length, and a second conduit for the egress of air from the room, said second conduit including a branch extending alongside said first branch and open at its lower portion for the ingress of air thereto along its length in a stratum at a level lower than that of the level of egress of air from said first branch.

33. In combination, a storage room and a source of temperature affected air supply, a pair of conduits, each of said conduits including a branch, one extending medially along the ceiling of the room and alongside the other, one opening at its lower portion for the egress of air therefrom along its length and the other open at its upper portion for the ingress of air along its length, a blower for impelling air from said source into one of said conduits, the other conduit leading from the room.

34. In combination, a storage room and a source of temperature affected air supply, a conduit for conducting air into the room and a blower for impelling air from said source into the conduit, said conduit being arranged to direct the flow of air therefrom medially of the room along the ceiling thereof, a second conduit extending along the ceiling of the room medially thereof and open along its length, said second conduit leading from the room, the outlet from the first conduit and the opening in the second conduit being at relatively different elevations.

35. In combination, a storage room, a first chamber and a second chamber, the room being in communication with each chamber, temperature affecting means within each chamber, a conduit within the first chamber communicating with the outside and through which air, affected by said means, gravitates into said chamber, a fan for blowing air from the first chamber into the second chamber, and means for the escape of air from the second chamber to the outer air.

36. In combination, a storage room and an adjoining chamber, said room being in communication with said chamber and also with the outer air, temperature affecting means in said chamber, a conduit, within said chamber communicating with the outside and through

which, affected by said means, gravitates into the chamber, and a fan for blowing air from the chamber into said room.

37. In combination, a storage room and a chamber, upright baffles in said chamber staggered to form a horizontally winding passageway therein, said baffles, in part, including connected pipes conveying therethrough a temperature affecting medium, a blower receiving its air supply from the room and discharging into one end of said passageway, said chamber at the other end of said passageway being in communication with said room.

38. In combination, a storage room and a chamber, upright baffles in the chamber staggered to form a horizontally winding passageway therein, said baffles, in part, including connected pipes conveying therethrough a refrigerating medium, a blower receiving its air supply from the upper stratum in the room and discharging into one end of said passageway, means for conducting air from the lower portion of said chamber at the other end of said passageway to the room at a level beneath that of said upper stratum, said refrigerant conducting pipes extending in the direction of flow of air through said passageway.

39. In combination, a storage room and a chamber, upright baffles in the chamber staggered to form a horizontally winding passageway therein, said baffles, in part, including conduits for a refrigerating medium, the upper portion of said chamber at one end of said passageway being in communication with the upper portion of the room at one elevation, the lower portion of said chamber at the other end of said passageway being in communication with said room at a lower elevation at the other end of said passageway.

40. In combination, a storage room and a chamber communicating with said room, temperature affecting means within the chamber, a blower receiving its air supply from said room and the outer air and discharging into said chamber, and valved means of egress for air from the chamber at the upper portion thereof and at its lower portion.

41. In combination, a storage room and a chamber communicating with said room, temperature affecting means within the chamber, a blower receiving its air supply from said room and the outer air and discharging into said chamber, an upright pipe in the chamber in valved communication at its upper end with the upper portion of said chamber and in valved communication at its lower end with the lower portion of said chamber, and an egress branch issuing from said pipe, between its ends, and extending to the outside of said chamber.

42. In combination, a room, a conduit assembly including two branches disposed

medially longitudinally of said room adjacent the ceiling thereof, one open along its length to the interior of the room at one elevation and the other similarly open to the room at a different elevation, said assembly including means for the ingress of gravitating air to one branch and means for the egress of gravitating air from the other branch.

43. In combination, a room, a conduit assembly in said room disposed medially thereof and including two branches disposed medially longitudinally of said room adjacent the ceiling thereof, one open along its length to the interior of the room at one elevation and the other similarly open to the room at a different elevation, said assembly including means for the ingress of gravitating air to one branch and means for the egress of gravitating air from the other branch, means for drawing the air from one branch and impelling it into the other and means for changing the temperature of the air in transit from one branch to the other.

44. In combination, a room, an overhead air ingress conduit extending medially longitudinally of the room and opening along its length into the interior of said room, an egress conduit extending longitudinally of the room and also opening along its length to the interior thereof, means for impelling into the room air of relatively low temperature via said ingress conduit, said egress conduit being located to receive air from the room which has first descended centrally therein and thereafter moved outwardly and upwardly in its natural gravitating cycle within the room.

45. In combination, a room, an overhead air ingress conduit extending medially longitudinally of the room and opening along its length into the interior of said room, an egress conduit extending longitudinally of the room and also opening along its length to the interior thereof, means for impelling into the room air of relatively different temperature via the ingress conduit, said egress conduit being located to receive air which has moved in directions outwardly and through different elevations in its natural gravitating cycle within the room.

46. In combination, a room, an overhead conduit for introducing refrigerated air into the room, extending medially longitudinally thereof and opening along its length into the interior of said room at a level spaced beneath the ceiling, and suction means for taking off from the ceiling of the room air which has first descended centrally therein from said first duct and thereafter moved outwardly and upwardly in its natural gravitating cycle within the room.

47. In an apparatus of the class described, a chamber, an appliance therein including two upright ducts, means for affecting the temperature of said ducts, each duct being

in valved communication at its upper ends with the upper portion of the chamber and with the outer atmosphere and each duct being in valved communication at its lower end with the lower portion of the chamber and with the outer atmosphere.

48. In combination, a storage room and chamber, upright baffles in the chamber staggered to form a horizontally winding passageway therein, said baffles, in part including connected pipes conveying therethrough a refrigerating medium, a blower, a suction conduit for the blower having a branch extending along the ceiling of the room midwidth thereof and receiving its air supply from along the same at the uppermost stratum in the room, said blower discharging into one end of said passageway, a second conduit for conducting air from the lower portion of said chamber at the other end of said passageway, said second conduit having a branch extending along the ceiling of the room midwidth thereof and adapted to discharge air therefrom along the same at a level adjacent to but beneath that of the uppermost stratum.

49. In combination, a storage room, a source of supply of temperature affected air, two conduits, one an air ingress conduit leading from said source to the room and the other an air egress conduit leading from the room back to said source, said conduits communicating at the same proximity, though at different levels, with the interior of the room, through one wall of the room near the ceiling and midway between other opposite walls of the room.

In testimony whereof, I have signed my name to this specification.

CHARLES A. MOORE.
